CASH REGISTER

Robert E. Boyden and Holland H. Freeman, Los Angeles, Calif., assignors to Clary Multiplier Corporation, Los Angeles, Calif., a corporation of California

Application November 12, 1947, Serial No. 142,498

Term of patent 14 years

(Cl. D64—11)

To all whom it may concern:

Be it known that we, Robert E. Boyden and Holland H. Freeman, both citizens of the United States, and residents of the city of Los Angeles, in the county of Los Angeles and State of California, have invented a new, original, and ornamental Design for a Cash Register, of which the following is a specification, reference being had to the accompanying drawing, forming part thereof, and wherein:

Fig. 1 is a perspective view of a cash register, showing our new design,

Fig. 2 is a side view thereof,

Fig. 3 is an end view thereof, and

Fig. 4 is a plan view thereof.

The essential and novel features of our design reside in the parts shown in full lines, among which are the pyramidal arrangement, when viewed from the rear, comprising a vertically extending central section flanked by two ver-

tically extending side sections which rest on a base portion extending outward substantially from the side sections and form the base of the machine, the central section curving upwardly and forwardly.

We claim:

The ornamental design for a cash register, substantially as shown and described.

ROBERT E. BOYDEN.
HOLLAND H. FREEMAN.
